UNITED STATES PATENT OFFICE.

WILLIAM T. RICHARDS, OF QUINCY, MASSACHUSETTS.

LACING-HOOK.

No. 884,682.

Specification of Letters Patent.

Patented April 14, 1908

Application filed May 11, 1907. Serial No. 373,063.

To all whom it may concern:

Be it known that I, WILLIAM T. RICHARDS, of Quincy, in the county of Norfolk and State of Massachusetts, have invented certain new and useful Improvements in Lacing-Hooks, of which the following is a specification.

This invention relates to a lacing hook for use on boots and shoes and other articles secured by lacings, and it has for its object to provide a lacing hook adapted to securely engage the lacing, and prevent the possibility of the accidental movement of the lacing outwardly from under the terminal portion of the hook, the construction being such that the hook is protected and guarded so that it cannot engage a garment which may project over the hook.

The invention also has for its object to provide a lacing hook of the character above noted, which shall be of compact form, the length of the device as a whole being reduced to the minimum.

The invention consists in the improvements which I will now proceed to describe and claim.

Of the accompanying drawings, forming a part of this specification,—Figure 1 represents a side elevation of a lacing hook embodying my invention. Fig. 2 represents an end elevation of the same, and Fig. 3 represents a top plan view.

The same letters of reference indicate the same parts in all the figures.

My improved lacing hook is preferably made from a sheet metal blank, although I do not limit myself to this material. In the embodiment of my invention here shown, the hook is composed of a sheet metal base portion 12, adapted to bear on a portion of the upper of a boot or shoe, and provided with suitable attaching means, preferably an eyelet 13, adapted to pass through the portion of the upper on which the hook is located, and to be spread or upset to secure the hook. Any other suitable attaching means may be employed.

The blank from which the hook is made, has an extension, which is bent outwardly from the plane of the base 12 to form a hook composed of a neck portion 14 and a terminal portion 15, the latter overhanging the base. The terminal portion 15 is considerably narrower than the base, and its outer extremity is preferably curved inwardly toward the base, as shown in Figs. 1 and 2.

16 16 represent guards, which are formed by providing the blank with lateral extensions, these being bent upwardly from the base portion, and standing at opposite edges of the terminal portion of the hook, from which portion they are separated by spaces through which the lacing may be passed. The terminal portion 15 of the hook projects between the guards, its outer 60 surface being substantially flush with the upper portions of the edges of the guards, as shown in Fig. 1. The inner edges of the guards, or those which are opposed to the neck portion 14 of the hook, are therefore 65 considerably nearer the said neck portion than the outer end of the terminal portion 15. The said inner edges therefore constitute stops, which prevent the bight, or portion of the lacing which is engaged with the neck 14, 70 from slipping outwardly toward the outer end of the terminal portion 15, as indicated in Figs. 1 and 2, where the lacing 18 is indicated by dotted lines.

It will be seen that the lacing may be engaged with the hook, either by threading it through the opening bounded by the neck 14, the terminal portion 15 and the inner edges of the guards 16, as shown in Fig. 1, or by looping the lacing, and passing the bight of 85 the loop between the outer end of the terminal portion 15 and the base 12, the sides of the loop being passed through the spaces between the edges of the terminal portion and the guards, and the loop being drawn back 90 until it comes to a bearing on the neck 14. When the loop is in place, it is prevented by the guards from slipping outwardly and reaching the outer end of the terminal portion 15. The upper and outer edges of the 95 guards prevent the possibility of skirts or other garments catching in the outer end of the terminal portion of the hook. Another advantage of the guards 16 is that since they project upward in vertical planes, they form 100 uprights which protect the hook 15 from receiving such pressure as might bend it down or flatten it.

My invention is distinguished from any lacing hook heretofore made, so far as I am 105 aware, by the fact that the terminal portion of the hook projects between guards located at opposite edges of the hook, the outer end of the terminal portion of the hook being farther from the neck of the hook than the inner 110 edges of the guards. This distinguishing characteristic results in the more secure en-

gagement of the lacing with the hook than heretofore, and reduces the length of the hook to the minimum, so that the hook has a compact form, which conduces to its stiffness and strength, and gives it a desirable appearance.

I claim:

1. A lacing-hook comprising a base having means for attachment to a support, a hook integral with the base and having a neck portion rising from one end of the base, and a terminal portion overhanging the base, and guards also integral with the base and projecting outwardly therefrom at opposite edges of the hook, the terminal portion of the hook projecting between the guards, whereby the hook is protected or guarded by the upper and outer edges of the guards, while the inner edges of the guards form stops which face toward the neck portion of

the hook and are adapted to prevent outward movement of a lacing from said neck portion to the outer end of the terminal portion of the hook.

2. A lacing-hook comprising a base having means for attachment to a support, a hook integral with the base and having a neck portion rising from one end of the base and a terminal portion overhanging the base to form a hook, and integral upright guards rising from the base at opposite edges of the hook portion, the upper edges of said guards being in a plane at a height to protect the hook portion from being bent downward.

In testimony whereof I have affixed my signature, in presence of two witnesses.

WILLIAM T. RICHARDS.

Witnesses:

C. F. BROWN,
ARTHUR H. BROWN.
